UNITED STATES PATENT OFFICE

ARTHUR E. PEW, JR., OF BRYN MAWR, PENNSYLVANIA, ASSIGNOR TO SUN OIL COMPANY, OF PHILADELPHIA, PENNSYLVANIA, A CORPORATION OF NEW JERSEY

PROCESS OF CRACKING MINERAL OIL

Application filed November 9, 1929. Serial No. 405,871.

In order to crack, in the vapor phase, crude oil or any product, such as gas oil, resulting from the distillation of crude oil, in order to produce comparatively low boiling products such as gasoline, such oil as is passed through the vapor phase cracking zone should not only be completely vaporized; but it is important that the vapor should be perfectly dry. An oil may be so completely vaporized that no entrained liquid may be separated therefrom by any mechanical device for throwing out any entrained liquid, but it may still contain sufficiently very finely divided particles or very moist vapors that are practically at the dew point, in consequence of which, when the vapors are exposed to moderately high temperatures, there is a decided formation of carbon on the metal surface through which the heat is conducted to the vapors. The amount of carbon so formed is relatively very small, but it builds up on the metal walls and in time so reduces or obstructs the flow that it is necessary to shut down the equipment for cleaning. It is, of course, obvious that one method of overcoming this difficulty is to superheat or raise the temperature of the vapors so that they are completely dried and free of any moisture or finely divided entrainment. This method has been used for this purpose with proper distribution of heating surface. In a very mild form of heating this can be done with a reasonable degree of success. When, however, the drying of the vapors is effected in this way, the lack of uniform conditions, which it is almost impossible to maintain, militates against success. Any excessive temperature in the drying zone causes accumulation of carbon in a relatively short period, while any drop in temperature in the drying zone which does not fully dry the vapors, even for relatively short periods, allows the moist vapors to go into the cracking zone and thus form carbon very rapidly in the cracking tubes. Another cause of trouble with such an arrangement is that the carrying over of any actual liquid into the drying zone causes the formation of vapors in the drying zone, which then are saturated or even carry entrained liquid, thus introduc-

ing such saturated vapor or entrained liquid into the cracking tubes.

The process involving the present invention is intended and adapted to overcome these difficulties and to provide more positive means of completely drying the vapors before they are introduced into the vapor phase cracking zone. It involves the practice of a number of steps including the vaporization of the oil under a substantial pressure and the cracking of the oil under a much reduced pressure which need not exceed the back pressure of the cracking and fractionating equipment.

The entire process will first be described and the invention will then be particularly pointed out in the claims. The single figure of the drawing is a diagrammatic illustration of the apparatus which may be used.

The charging stock, preferably gas oil, is taken from the tank through line 1 and pump 2 through heat exchangers 3 and 150 into the pipe still 4, where it is heated up to practically completely vaporize the oil as it enters the vaporizer 5. The pump maintains in the vaporizer line a substantial pressure, say from 100-300 pounds. The vapors leave the top of vaporizer 5 and pass through a separator 6, which takes out any mechanical entrainment of liquid and prevents any liquid passing beyond this part of the line. Beyond separator 6 is a pressure reducing valve 7, which effects or allows a drop of 50 or more pounds of pressure, the reduced pressure not being necessarily higher (40 to 50 pounds) than the back pressure of the cracking and fractionating equipment. The vapor then passes through line 8 into the vapor phase cracking coil 9, is raised therein to the required or desired temperature (say about 950° F. or above) and passes out at 10 into the spray cooler tower 11, where it is cooled and partially separated. In tower 11 the heavier portion is drawn off at the bottom through outlet 12 and the remainder goes out as vapor through line 13 and into fractionating tower 16, where the lighter portions are separated. Gasoline and gas go out through line 17, through a clay tower 23 and through a condenser 24 into a gas separator 30, from

which gasoline is taken out through line 31. The gas escapes through line 32 into an absorption tower 33 and the stripped gas is passed out through line 34 to a gas holder 5 or to the atmosphere.

From tower 16 an intermediate product is taken out through line 19 and, after passing the heat exchanger 3 and/or other coolers, goes to storage; or it may be used again in the 10 process by being conducted through by-pass line 190 to the feed or charging stock line; the product being very similar to the original gas oil which is used as charging stock.

All of the gasoline vapors and gas are not 15 taken out of tower 16 through line 17, but a regulable proportion is taken out through line 18 and passes through condenser 26 into tank 27; the condensate being taken through pump 28 and line 22 back into the top of the 20 fractionating tower. This condensate is used for controlling the temperature at the top of the tower in order to fix the maximum boiling point of the product taken through line 17. Line 29 is the vent which vents the gas from 25 tank 27 so as to maintain the proper level of liquid in this tank.

The condensate in tower 16 is conducted back to the upper part of tower 11, where it promotes or effects the cooling and fractionation of the cracked vapors from the cracking coil 9, and controls the outlet temperature through line 18. This condensate is 30 conveyed to tower 11 through lines 20 and 15, being cooled, by heat exchanger, at 150, with 35 incoming charging stock. The line 50, which leads from the outlet at the bottom of vaporizer 5, is for conveying away any heavy ends which may not be completely vaporized when the oil leaves the pipe still. This high boiling 40 product may be carried back into line 15, as shown, or may be withdrawn from the system. If a relatively heavy charging stock, such as a topped crude, is used, then a considerable 45 portion is drawn off at the bottom of vaporizer 5 and this should then be passed through line 14 into tower 11. Such heavy portions are exposed to the highest temperature in tower 11 and in this way cracked to some extent and the heavy portions are drawn 50 off through line 12 along with the heavy products from the vapor phase cracking coil.

Due to the substantial pressure maintained in the pipe still and vaporizer, it is, of course, necessary to maintain a comparatively high 55 temperature in the vaporizer in order to vaporize any desired percentage of the oil passing through the pipe still. For example, if a gas oil having an average boiling point of 525° F. is used as a charging stock and if a 60 vaporizer pressure of only 50 pounds were maintained, it would require a temperature of not much over 700° F. to completely vaporize this oil. If, however, as in the practice of my process, a substantially higher 65 pressure (say 250 pounds) is maintained in

the vaporizer, a temperature of about 840° F. is required to completely vaporize this oil. This is approximate only, and will vary with the nature and the source of the oil. Whatever the pressure may have been, the vapors are in a saturated condition and, therefore, are not in suitable condition to put into the high temperature vapor phase cracking zone. When, however, as in my process, the pressure on the oil vapors is materially reduced, 70 the vapors are converted into a superheated condition, or, in other words, they are no longer saturated but at a temperature which is above the saturation point for the new pressure existing. This provides a vapor which 75 is thoroughly dried and free of any form of moisture. To accomplish this purpose, the pressure reduction may vary from 50 to 200 pounds. A suitable condition for operation, 80 under average conditions, is to maintain a pressure of about 250 pounds in the vaporizer and to reduce this pressure to about 100 pounds on the outlet side of the pressure reducing valve. The entire system may be operated at somewhat lower pressures; for example, the vaporizer may be run at 150 85 pounds or even less and may be reduced to 40 to 50 pounds on the outlet side of the pressure reducing valve 7. Maintaining the fractionating equipment at lower pressures still 90 allows sufficient pressure for passing the dry vapors through the cracking zone at the required velocities, and the fractionating equipment need be operated at only slightly above 95 atmospheric pressure.

The drying of the oil vapors may also be effected by combining the process herein described with the introduction of a small percentage of dry gas at about the temperature of the oil vapors into the line between the vaporizer and the cracking coil, as set forth in an application, Serial No. 405,870, filed of even date herewith.

Having now fully described my invention, what I claim and desire to protect by Letters 110 Patent is:

1. The process of cracking a mineral oil charging stock which comprises vaporizing the oil under a substantial superatmospheric pressure, drying the oil after it has expanded into vapor by suddenly reducing the pressure thereon not less than 50 pounds per square inch to the extent required to bring the temperature above the saturation point for the reduced pressure, then heating the oil vapors under the reduced pressure to a cracking temperature and cracking the vapors, and then cooling and fractionating the vapors.

2. The process of cracking a mineral oil charging stock which comprises heating the oil and thereby vaporizing it under a substantial superatmospheric pressure, allowing the vapors to expand beyond the heating zone and removing heavy fractions, then

- drying the oil vapors by reducing the pressure thereon not less than 50 pounds per square inch to the extent required to bring the temperature above the saturation point 5 for the reduced pressure, then heating the oil vapors under the reduced pressure to a cracking temperature and cracking the vapors, and then cooling and fractionating the vapors.
- 10 3. The process of cracking a mineral oil charging stock which comprises heating the oil and vaporizing it under a pressure of from about 100 to 300 pounds, drying the oil after it has expanded into vapor by suddenly 15 reducing the pressure thereon about 50 to 200 pounds and thereby drying the oil by bringing the temperature above the saturation point for the reduced pressure, then heating the oil vapors under the reduced 20 pressure to a cracking temperature and cracking the vapors, and then cooling and fractionating the vapors.
4. The process of cracking a mineral oil charging stock which comprises vaporizing the oil under a pressure of about 150-300 pounds at a temperature of about 750-900° F., suddenly reducing the pressure on the oil after it is expanded into vapor about 100 pounds or less, thereby drying the oil by 30 bringing the temperature above the saturation point for the reduced pressure, then heating the oil vapors under the reduced pressure to a cracking temperature substantially above the temperature at which it was 35 vaporized, and then cooling and fractionating the vapors.
5. The process of cracking a mineral oil charging stock which comprises flowing the stock in an elongated stream of restricted 40 cross-section through a heating zone and then into an enlarged space beyond the heating zone and maintaining the stock under substantial superatmospheric pressure, heating the stock while it is flowing through said 45 stream to such temperature that substantially all of it will be in vapor phase in the enlarged space, then conducting the vapors beyond the enlarged space and suddenly substantially reducing the pressure on the oil 50 vapors not less than 50 pounds per square inch to the extent required to bring the temperature above the saturation point for the reduced pressure, and then heating the oil vapors under such reduced pressure to a 55 cracking temperature and cracking the vapors, and cooling and fractionating the vapors.
6. The process of cracking a mineral oil charging stock which comprises flowing the 60 stock in an elongated stream of restricted cross-section through a heating zone and then into an enlarged space beyond the heating zone and maintaining the stock under substantial superatmospheric pressure, heating the stock while it is flowing through said
- stream to such temperature that substantially all of it will be in vapor phase in the enlarged space, removing from the vapors any entrained liquid, then conducting the vapors beyond the enlarged space and suddenly substantially reducing the pressure on the oil vapors, not less than 50 pounds per square inch to the extent required to bring the temperature above the saturation point 70 for the reduced pressure, and then heating the oil vapors under such reduced pressure to a cracking temperature and cracking the vapors, and cooling and fractionating the vapors.
7. The process of cracking a mineral oil charging stock which comprises heating the oil, vaporizing the larger part and separating and removing any unvaporized heavy ends and entrained liquid, conducting said operations under substantial superatmospheric pressure, then drying the oil vapors by suddenly reducing the pressure thereon by an amount not less than 50 pounds per square inch to the extent required to bring the temperature above the saturation point 80 for the reduced pressure, then heating the dried oil vapors under the reduced pressure to a cracking temperature and cracking the vapors, and then cooling and fractionating the vapors.
- In testimony of which invention, I have hereunto set my hand, at Philadelphia, Pennsylvania, on this 7th day of November, 1929.
